UNITED STATES PATENT OFFICE

113,142

DESIGN FOR A BREAD BOX

Meyer Kamenstein, New York, N. Y.

Application July 9, 1938, Serial No. 78,372

Term of patent 7 years

To all whom it may concern:

Be it known that I, Meyer Kamenstein, a citizen of the United States and a resident of the city, county, and State of New York, have invented a new, original, and ornamental Design for a Bread Box, of which the following is a specification, reference being had to the accompanying drawing, forming a part thereof.

In the drawing, the figure is a perspective view of a bread box, showing my new design.

I claim:

The ornamental design for a bread box, as shown.

MEYER KAMENSTEIN.
